UNITED STATES PATENT OFFICE

115,028

DESIGN FOR A SANDAL OR SIMILAR ARTICLE

Herschel S. Davis, Little Rock, Ark.

Application April 3, 1939, Serial No. 83,997

Term of patent 14 years

To all whom it may concern:

Be it known that I, Herschel S. Davis, a citizen of the United States, residing at Little Rock, in the county of Pulaski and State of Arkansas, have invented a new, original, and ornamental Design for a Sandal or Similar Article, of which the following is a specification, reference being had to the accompanying drawing forming part thereof.

Fig. 1 of the drawing is a plan view of a sandal embodying my new design;

Figs. 2 and 3 are side views showing the outer and inner sides, respectively, of the sandal of Fig. 1 as it is worn on the foot; and

Fig. 4 is a rear view of the heel engaging portion only of the sandal shown in Figs. 1, 2, and 3.

I claim:

The ornamental design for a sandal or similar article, as shown.

HERSCHEL S. DAVIS.
